UNITED STATES PATENT OFFICE

WILLIAM D. ANTRIM, OF GLOUCESTER, NEW JERSEY, ASSIGNOR TO ROBERTS & MANDER STOVE COMPANY, OF PHILADELPHIA, PENNSYLVANIA, A CORPORATION OF PENNSYLVANIA

SAFETY GAS VALVE

Application filed January 28, 1931. Serial No. 511,845.

The object of my invention is to provide a valve which controls the flow of gas to the oven and to the broiler of a gas range so as to prevent accidents due to the accidental flowing of gas to one burner when gas is flowing and ignited at the other burner. This object I attain in the following manner, reference being had to the accompanying drawings, in which:

10 Fig. 1 is a plan view of my improved combination gas valve illustrating my invention; Fig. 2 is a sectional view on the line 2-2,

Fig. 1;

Fig. 3 is a diagrammatic view showing the locking plate moved so as to allow the valve to be turned to permit gas to flow to the right-hand passage as shown by dotted lines in Fig. 1, or in reverse direction to a stop, cutting off gas to both burners;

20 Fig. 4 is a similar view to Fig. 3, showing the locking plate lowered, allowing the valve to be turned to permit gas to flow through the left-hand passage and closing the right-hand passage;

25 Fig. 5 shows the locking plate accidentally raised and in a position in respect to the lugs on the valve stem, so that said lugs will return the plate to the position shown in Fig. 4 when the gas valve is turned to shut the

30 left-hand side of the valve;

Fig. 6 is a view showing the locking plate in mid-position, locking the valve against movement in either direction;

Fig. 7 is a detached perspective view of the

35 valve;

Fig. 8 is a detached view of the indicator plate;

Fig. 9 is a front view of sufficient of a gas range to show the improved gas valve located

40 back of the front panel of the range, the panel having a slot therein to expose an indicator plate; and

Fig. 10 is a sectional view on the line

10-10, Fig. 9.

45 1 is the casing of the valve structure, 2 is a valve. This valve is tapered in the present instance as shown in Fig. 7, and is held to its seat by a spring 3 bearing upon a washer 4, which rests against the casing, and a head 5

50 which is a continuation of the valve stem.

6 is the valve stem, having a handle 7 of any type desired. The valve casing is cut away at 8, forming stops 9 and 10 for the pin 27 on the valve 2, Fig. 2. The stop 9 limits the movement of the valve when in position to 55 open the right-hand passage 11 in the valve casing, and the stop 10 limits the movement of the valve when the left-hand passage 12 is open. 13 is the gas inlet nipple, which is threaded as shown in Fig. 2 and is adapted to 60 be connected to the gas manifold of the range.

On the valve stem 6 are two lugs 14-14a, diametrically opposite each other. Pivoted at 15 to an extension 16 of the valve casing is 65 a locking plate 17, having a handle 18. The locking plate can be moved either into an upper position, a lower position, or a central position, and is frictionally held in the position to which it is adjusted by means of a 70 flat spring 19, which bears against the back of a projection 20 of the valve casing, Fig. 1. Other means of providing friction for this plate may be used without departing from the essential features of the invention. 75

The plate has an opening 21 therein, and this opening is made as shown in Fig. 3, the portion 22 of the opening being less in width than the main portion 21 of the opening, forming abutments 23 and 24 for the lugs 14 80 of the valve stem, and the walls of the portion of the opening 22 providing cam surfaces 25 and 26, which when the plate is accidentally moved out of position, one or the other of the lugs 14-14a when the valve stem is turned 85 will return the plate to the position to which it was adjusted. The faces of the stops 23 and 24 are at right angles to a line drawn through the pivot 15 of the plate, and the sides of the lugs 14-14a are undercut on the same lines, and this construction tends to prevent the accidental movement of the plate. If it is desired to allow gas to flow through the right-hand gas passage 11 in the valve 90 casing, then the plate is raised to the position shown in Fig. 3, and the valve stem is free to turn in the direction of the arrow (Fig. 3), until the pin 27 on the valve strikes the stop 9 when the connection between the inlet opening 13 and the passage 11 is full 95 100

open. To turn off the gas, the valve is turned in the opposite direction until the stop 14a strikes the abutment 23. Then if it is desired to move the plate 17 so that the left-hand passage will be open to the inlet 13, the plate is moved to the low position shown in Fig. 4, the stop 24 preventing the movement of the lug 14 opposite to the direction of the arrow, Fig. 4, but will allow the valve stem to be moved in the direction of the arrow until the pin 27 on the valve strikes the stop 10 of the valve casing. Then the passage 12 will be full open and the passage 11 will be closed and the plate will lock the valve stem so that it is impossible to open the passage 11 while the passage 12 is open. If the plate 17 is accidentally raised, as in Fig. 5, then the lug 14a will strike the cam surface 26 of the portion 22 of the opening and will return the plate to the low position as illustrated in Fig. 4. The same operation takes place when the plate is in the raised position, as shown in Fig. 3, and is accidentally lowered. Then the lug 14 will strike the cam surface 25 of the opening 22 and return the plate to its raised position. When the plate is in the mid-position, as shown in Fig. 6, the lugs 14—14a will rest against the stops 24 and 23, respectively, and lock the stem from moving in either direction.

By the above description it will be seen that I provide a very simple and effective safety device for the gas valve controlling the flow of gas to the burners of the oven and the broiler, the device being located directly at the valve so that the plate can be readily adjusted to direct the gas to the proper channel.

In Figs. 9 and 10 I have shown my improved gas valve located back of an apron of a gas range. 28 is the top of a range. 29 is the front plate, and 30 is an apron extending from the top plate to a point below the manifold and gas valve. The stem 6 of the gas valve extends through an opening in the apron 30, the handle 7 being on the outer side of the apron.

The handle 18 of the plate 17 extends through a slot 31 in the apron. In order to indicate clearly the position of the valve, an indicator plate 32 is secured to the plate 17 as shown in Figs. 1 and 8, and on this plate 32 are the words "Broil" and "Bake." The slot 31 in the apron 30 is preferably elongated at top and bottom as at 33 and 34, to expose the words on the plate 32 when the plate 17 is in a given position, indicating the position of the valve. For instance, when the plate is raised, then the word "Broil" is exposed in the slot, and when the plate is lowered the word "Bake" is exposed in the lower portion of the slot. The design of apron is immaterial and can be made in many different ways. It will be understood that while I have shown the slot for the handle elon-

gated at its upper and lower end, independent slots may be provided to expose the words without departing from the essential features of the invention.

I claim:

1. The combination of a gas valve structure having two gas passages; a valve arranged to open either gas passage; and a movable plate having stops to limit the movement of the valve, so that when the plate is in one position, one passage can be opened and the valve will be locked against opening the other passage, and when the plate is moved to its other position the other passage can be opened and the valve locked against opening the first-mentioned passage. 70

2. The combination in a valve structure having two outlet passages and an inlet passage therein; a valve controlling the flow of gas to said passages from the inlet passage, said valve having a stem; a handle on the stem; two lugs on the stem; and a plate pivoted to the valve structure and having stops thereon, said plate being arranged to be moved, so that one of the lugs will strike one stop and when the plate is moved in the opposite direction, the other lug will strike the other stop. 85

3. The combination in a valve casing having an inlet passage and two outlet passages, of a valve controlling the flow of the gas from the inlet passage to either one of the outlet passages; a stem on the valve; a handle on the stem; diametrically opposite lugs on the stem; a plate pivoted to the valve casing between the handle and said casing and having an opening therein; two stops on the plate, the stem extending into the opening; and two diametrically opposite lugs on the stem within the opening in the plate, the parts being so arranged that when the plate is raised the valve can be turned in one direction and stopped when turned in the opposite direction, and when the plate is lowered the valve can be turned in the opposite direction and stopped from turning in the first-mentioned direction. 105

4. The combination in the casing of a valve structure having a central inlet opening and two side outlet passages, of a valve controlling the flow of gas from the inlet opening to the outlet passages; a pin on the valve and stops on the valve casing; a valve stem and a handle, the stem having diametrically opposite lugs; and a plate located between the casing and the handle and pivotally mounted on the casing, said plate having an opening through which the stem and its lugs extend, the opening having a reduced portion forming stops and cam surfaces so that when the plate is raised one stop will form an abutment for the one lug and when the plate is lowered the other stop will form an abutment for the other lug, and when the plate is accidentally moved from the position 115

tion to which it is set, one of the lugs will act upon the cam surface of the plate and return the plate to its set position.

5. The combination in a valve casing having an inlet opening and two outlet passages, of a valve controlling the flow of gas through said passages; a stem on the valve; a handle on the stem; lugs on the valve stem; and a plate pivoted to the casing and having an opening therein and two stops, one for one lug and the other for the other lug, the face of each stop being on lines at right angles to the lines drawn through the center of the pivot of the plate, the sides of the lugs being undercut on the same lines so that they will interlock with the stops on the plate.

6. The combination in a valve casing having an inlet opening and two outlet passages, of a valve controlling the flow of gas from the inlet opening to the outlet passages; a pin on the valve and two stops on the valve casing for limiting the movement of the valve; a stem on the valve; lugs on the stem; a plate pivoted to the casing and having an opening therein through which the stem and its lugs extend; stops on the plate extending into the opening to limit the movement of the stem; a spring secured to the plate; and a lug on the casing, back of which the spring extends so as to frictionally hold the plate in the position to which it is adjusted.

7. The combination in a valve casing having an inlet opening and two outlet openings, of a valve controlling the flow of gas from the inlet opening to the outlet passages; stops on the casing; a pin on the valve, limiting the movement of the valve in either direction; a stem on the valve; diametrically opposite lugs on the stem; a handle on the stem; and a plate pivoted to the casing and having a handle by which it is moved, the plate having an opening through which the stem and its lugs extend, the opening having a reduced portion forming two stops and two cam surfaces, the stops limiting the movement of the valve to a quarter turn in one direction or the other, according to the location of the plate, so that when the plate is raised the gas will flow from the inlet opening to one outlet passage and when the plate is lowered the gas will flow from the inlet opening to the opposite outlet passage, and when the plate is accidentally moved from its said position, one of the lugs will strike the cam surface on the plate and return the plate to its said position.

8. The combination in a gas range having baking and broiler burners, of a gas valve common to both burners, the casing of the valve having an inlet passage and two outlet passages, one passage arranged to be connected with a baking burner and the other passage arranged to be connected to a broiling burner; an apron on the range back of which the valve casing is mounted; a stem

on the valve extending through an opening in the apron; a handle on the stem on the outer side of the apron; a stop plate pivoted to the valve casing, forming a stop to limit the movement of the valve, so that when the valve is turned to open one outlet passage the other outlet passage is closed; a handle on the plate; a slot in the apron through which the handle of the plate extends; an indicator on the stop plate having two words thereon; and upper and lower slots in the apron so arranged that when the stop plate is raised a word will be exposed through the upper slot, and when the stop plate is lowered another word will be exposed through the lower slot.

9. The combination in a gas valve adapted for use in connection with a baking oven and broiling oven, of a gas range, said casing of the valve having two outlet passages connecting with the baking burner and the broiling burner respectively; an apron back of which the valve casing is mounted; a stem on the valve extending through an opening in the apron; a handle on the end of the stem; a plate through which the stem extends forming a stop to limit the movement of the valve, so that when one valve is open the other is closed; a handle on the plate; a vertical slot in the apron through which the handle extends, said slot having a longitudinal elongation at its upper and lower end; and an indicator carried by the plate and having the words "Broil" and "Bake" thereon, the word "Broil" being exposed through the upper elongation of the slot when the plate is moved in one direction, and the word "Bake" exposed through the other elongation when the plate is moved in the opposite direction.
